UNITED STATES PATENT OFFICE.

SAMUEL SWEENEY, OF SHARPSBURG, PENNSYLVANIA.

FLUSHING DEVICE FOR WATER CLOSETS.

Application filed February 9, 1923. Serial No. 617,991.

This invention relates to flushing devices for water closets, and has for its object to provide a device of such class, in a manner as hereinafter set forth, which functions to automatically effect the flushing operation when the seat member is elevated.

Further objects of the invention are to provide a flushing device for the purpose set forth which is simple in its construction and arrangement, strong, durable and efficient in its use, positive in its action, readily set up relative to the bowl, and comparatively inexpensive to manufacture.

With the foregoing and other objects in view which will appear as the description proceeds, the invention consists of the novel construction, combination and arrangement of parts hereinafter fully described and illustrated in the accompanying drawing, wherein is shown an embodiment of the invention, but it is to be understood that changes, variations and modifications can be resorted to which come within the scope of the claims hereunto appended.

In the drawing wherein like reference characters denote corresponding parts throughout the several views:

Figure 1 is a side elevation of a water closet of the ordinary tank type showing the adaptation therewith of a flushing device in accordance with this invention.

Figure 2 is a similar view illustrating the device in connection with a flush valve type of water closet.

Figure 3 is an enlarged detail sectional view of the upper end of the actuating rod and associated parts.

Figure 4 is a modified form of the device shown in connection with a closet of the flush valve type.

Figure 5 is a fragmentary top plan view of the bowl and seat members illustrating their hinged connection.

Referring in detail to Figure 1 of the drawing 1 denotes the bowl of a water closet and 2 the seat member, the latter having its rear end hinged, as at 3, with the bowl.

A flush tank 4 of the usual construction and operation is positioned at the rear of the bowl 1 and is provided with a rearwardly extending flush handle 5, which is adapted to be depressed to effect the flushing operation.

Fixed to the exterior of the tank 4 is a pair of brackets 6 and 7, the former being arranged above the latter and formed with a

vertical disposed adjustable stop 8 for the purpose to be described. An actuating rod 9 is mounted for vertical movement in the brackets 6 and 7, and has its lower end pivotally connected, as at 10, to the rear end of the operating lever 11, which latter is fixed to the rear portion of the seat member 2 in rear of the hinged connection 10 and moves in a direction opposite to the movement of the seat member 2 when the latter is elevated or depressed.

The upper end of the actuating rod 9 is formed with a vertical slot 12 in which a latch 13 is pivotally mounted. The rod 9 is formed with a lateral ear 14 to which the latch 13 is pivotally connected, as indicated at 15, so that when the latch 13 is hanging in the normal position its longitudinal vertical edge will project laterally through the slot 12. As the lower end of the latch 13 is adapted to engage and operate the flush handle 5, the arrangement of hanging the latch 13 will permit of a vertical pull relatively to its point of connection 15 and its point of contact with the flush handle 5. A spring 13' is mounted in upper end of the slot 12 and engages the latch 13 to normally maintain the latter in vertical alignment in the slot 12.

The upper end of the latch 13 is provided with a horizontally disposed arm 16 which is adapted to strike the stop 8 upon the downward movement of the rod 9 for the purpose of disengaging the latch 13 from the flush handle 5 after the flushing operation. Upon the upward movement of the rod 9, by the depression of the seat member 2, the latch 13 will return to the normal position by gravity and the action of the spring 13' to again engage the flush handle 5 when the rod 9 is shifted downwardly by the elevation of the seat member 2.

The construction and operation of the device shown in Figure 2, of the drawings, is identical to that described relative to the tank type of closet above described, with the exception that it is used in connection with a flush valve 17 which carries the brackets 6 and 7. The vertical movement of the rod 9 will cause the latch 13 to actuate the plunger 18 to effect the flushing operation.

The device shown in Figure 4, of the drawings, also illustrates the use of the device in connection with a flush valve 19, but in this construction the latch 13 does not

engage the plunger 20 but a horizontally disposed bar 21 which is pivotally carried as at 22, at the upper end of the support 23 fixed to the valve 19. The outer end of the bar 21 is provided with a pivoted depending weight 24, aligned to engage the plunger 20. In this construction the vertical movement of the rod 9 will cause the latch 13 to elevate the weight 24. When the latch 10 13 disengages the lever 20 the weight 24 will drop upon the plunger 20 and effect the flushing operation. The weight 24 will normally rest upon the plunger 20 and is of such weight as to allow the action of valve 15 spring to elevate the same slowly to thereby prolong the flushing operation. The impetus of the dropping weight 24 is intended to effect the flushing operation. The depression of the seat member 2 will cause 20 the automatic return of the lever 9 and latch 13 to the operating position.

What I claim is:—

1. A device for the purpose set forth comprising in combination with a flush device provided with a flush member adapted to be depressed and a closet seat having an elevating element and a rearwardly projecting lever fixed to said seat, a pair of brackets mounted on said device, an actuating rod slidably mounted for vertical movement in said brackets, and pivotally connected to said lever, the upper end of said rod being slotted, a spring controlled latch pivotally mounted in said slot and adapted 30 to operate said member when said rod is 35

shifted downwardly by the elevating movement of said seat, said latch formed with an arm, an adjustable stop carried by one of said brackets and adapted to engage said arm to disengage said latch from said flush member, and means for automatically returning said latch to the operative position when said seat is depressed. 40

2. A device for the purpose set forth comprising in combination with a flush device provided with a flush member adapted to be depressed and a closet seat having an elevating element and a rearwardly projecting lever fixed to said seat, a pair of brackets mounted on said device, an actuating rod slidably mounted for vertical movement in said brackets, and pivotally connected to said lever, the upper end of said rod being slotted, a spring controlled latch pivotally mounted in said slot, a support 50 carried by said device, a bar pivoted at the upper end of said support, a weight suspended from one end of said bar, said latch adapted to engage the other end of said bar to elevate the weight to cause the latter to 55 impart on said flush member to effect the flushing operation when the said seat is elevated, and means to automatically return the said latch to the operative position when the said seat is depressed, substantially as described and for the purpose set forth. 60

In testimony whereof I affix my signature.

SAMUEL SWEENEY.
